UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

CUTTER CHAIN.

Application filed November 1, 1924. Serial No. 747 318

My invention relates to cutter chains and more particularly to cutter chains for mining machines.

An object of my invention is to provide an improved cutter chain. A further object of my invention is to provide an improved cutter chain and especially an improved cutter chain adapted to use in connection with mining machines. Another object of my invention is to provide an improved cutter bit guard. A still further object of my invention is to provide an improved cutter chain having improved means carried thereby whereby the operator is prevented from being drawn into the rapidly moving chain even should he come in contact with the chain. Still another object of my invention is to provide an improved mining machine cutter chain having improved means carried thereby for guarding the points of the cutter bits. These and other objects and advantages of my invention will, however, hereinafter more fully appear.

In the accompanying drawings I have shown for purposes of illustration two forms which my invention may assume in practice.

In these drawings,—

Fig. 1 is a side elevation of a cutter chain constructed in accordance with my improvement.

Fig. 2 is a plan view of the chain shown in Fig. 1.

Fig. 3 is a transverse vertical sectional view taken substantially on line 3—3 of Fig. 1.

Fig. 4 is a detail view of a modified form of construction.

In this illustrative construction I have shown a cutter chain of usual construction comprising a cutter link 1 carrying a cutter bit 2 having an inwardly inclined cutting surface 3, projecting from the link 1, and a shank 4 rigidly held in position by means of a usual set screw 5, in a well known manner. The link 1 is connected to adjacent similar links, not shown, by means of usual intermediate straps or links 6 secured at opposite sides thereof and held in position by transverse rivets 7.

In my improved construction shown in Figs. 1 to 3 I have provided a bit shrouding or guard means 8 which is adapted to shroud a greater portion of the surface 3 of the bit 2. This shrouding member comprises a ver-

tical web 9 formed integral with the link 1 and arranged substantially in the longitudinal center line of the latter adjacent the forward end thereof and having a rearwardly inclined upper surface 10 and inclined sides 11 which terminate adjacent the outside edges 60 of the cutting surface 3 of the bit within the outer limits thereof, thereby causing the bit to present free cutting edges.

In the form of my invention shown in Fig. 4 I have provided the guarding member 8 with an inclined guarding or deflector portion 12, similar to the portion 9 shown in Figs. 1 to 3, and having rearwardly inclined sides 13 which converge into the outside edges of the cutting surface 3 of the bit 2, thus forming a smooth joint with the tapering sides of the bit.

In the operation of my improved construction shown in Figs. 1 to 3 it will be observed that the upper portion of the web 9 which shrouds or guards the greater portion of the surface 3 of the bit is disposed in such a manner that should the operator get too close to the exposed portion of the chain a relatively small portion of the cutting surface 3 of the bit would strike him or his clothing and, due to the movement of the chain and the shape of the surface 10 on the shrouding member 8, would throw him or his clothing out of the path of the bits. Otherwise the inwardly inclined surface 3 of the bit would catch him or his clothing and due to its shape would drag him into the mechanism, causing serious and frequently fatal injury. Also it will be observed that the small portion of the cutting surface 3 which projects beyond the edges of the shrouding member 8 is of sufficient size to efficiently cut the coal, in the usual manner.

In the operation of the form of my invention shown in Fig. 4 it will herein be noted that a guarding or deflector member 12 prevents the operator or his clothing from being dragged into the rapidly moving cutter chain, being even more effective in view of the more complete shrouding than the form of Figs. 1 to 3, though somewhat diminishing efficiency in cutting.

As a result of my improved construction it will be observed that the possibility of the operator being dragged into the rapidly moving cutter chain is greatly diminished, a relatively small cutting surface being exposed

which causes only a comparatively slight injury to the operator if struck thereby. It will further be observed that an improved cutter chain guard is provided which is of an exceedingly simple and inexpensive construction adapted to greatly diminish the danger of a rapidly moving cutter chain when exposed, and which in no way interferes with the effective operation of the cutter bits when in engagement with the work.

While I have in this application specifically described two forms which my invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. The combination with a cutter chain and a cutter bit having lateral cutting edges, of means carried by the cutter chain and projecting between said cutting edges for guarding a substantial portion of the cutting surface of the bit, said means having a guard surface inclined rearwardly from said chain to its outer extremity.

2. The combination with a cutter chain and a cutter bit having lateral cutting edges, of constantly operative means carried by the cutter chain independently of the bit and projecting upwardly between said cutting edges for guarding a substantial portion of the cutting surface of said bit, said means having a guard surface inclined rearwardly from said chain to its outer extremity.

3. The combination with a cutter chain and a cutter bit having lateral cutting edges, of means permanently carried by said chain having rigid relation with respect to said bit and projecting between said cutting edges for guarding a substantial portion of the cutting surface of said bit, said means having a guard surface inclined rearwardly from said chain to its outer extremity.

4. The combination in a cutter chain of a cutter link and a cutter bit carried by said link and having lateral cutting edges, said link having means formed integral therewith and projecting between said cutting edges for guarding a substantial portion of the cutting surface of said bit, said means having a guard surface inclined rearwardly from said chain to its outer extremity.

5. The combination in a cutter chain of a cutter link and a cutter bit carried by said link and having lateral cutting edges, said link having constantly operative means formed integral therewith and projecting upwardly between said cutting edges for guarding a substantial portion of the cutting surface of said bit, said means having a guard

surface inclined rearwardly from said chain to its outer extremity.

6. The combination with a cutter chain and a cutter bit having a forwardly inclined cutting surface and lateral cutting edges, of means formed on the cutter chain and projecting upwardly between said cutting edges for guarding a substantial portion of the cutting surface of said bit, said means having a guard surface inclined oppositely to said cutting edges from said chain to its outer extremity.

7. The combination with a cutter chain and a cutter bit having a forwardly inclined cutting surface and lateral cutting edges, of constantly operative cutter bit guard means carried by the cutter chain and projecting upwardly between said cutting edges, said guard means having a forward guard surface inclined rearwardly from said chain to its outer extremity.

8. The combination in a cutter chain of a cutter link and a cutter bit carried by said link and having a forwardly inclined cutting surface and lateral cutting edges, said link having cutter bit guard means formed integral therewith, said guard means having a forward surface inclined rearwardly from said chain to its outer extremity between said cutting edges.

9. The combination in a cutter chain of a cutter link and a cutter bit carried directly by said link and having a cutting surface having lateral cutting edges, said link having means projecting between said cutting edges and having inclined converging sides within the outer edges of said cutting surface for guarding a substantial portion of the latter, said means having a guard surface inclined rearwardly from said link to its outer extremity.

10. The combination with a cutter chain and a cutter bit provided with a tapered cutting end, of deflector means mounted in front of said bit, a portion of which extends over and adjacent to the point of said cutting end, said deflector means at all points being of less width than said cutting end of the bit so as not to hinder its cutting action.

11. The combination in a cutter chain of a cutter link and a cutter bit carried by said link and having a forwardly inclined cutting point, said link having guard means secured directly thereto forwardly of said bit, said means presenting a rearwardly inclined deflector surface extending outwardly from said link to adjacent said cutting point, and another deflecting surface in front of said point inclined rearwardly at a greater angle than said first surface, the extreme cutting edges of said point however being exposed for cutting action.

In testimony whereof I affix my signature.

MORRIS P. HOLMES.
